UNITED STATES PATENT OFFICE.

KARL HÖHN, OF SCHAFFHAUSEN, SWITZERLAND.

COUPLING FOR NON-CLOSABLE CIRCUIT-BREAKERS.

1,040,541.

Specification of Letters Patent. Patented Oct. 8, 1912.

Application filed January 24, 1911. Serial No. 604,297.

To all whom it may concern:

Be it known that I, KARL HÖHN, a citizen of the Helvetic Confederation, residing at Schaffhausen, in the Canton of Schaffhausen, Switzerland, have invented a new and useful Coupling for Non-Closable Circuit-Breakers or the Like, of which the following is a specification.

This invention has reference to a free-turning coupling for automatic non closable circuit breakers or the like, which enables the automatic releasing device of the latter to switch off the current even when the actuating member is locked in wholly or partly switched-on position by means of the operating member. For this purpose a lever being pivoted crosswise to the spindle, which lever can catch a second spindle and hold it fast by means of a locking member in the switched-on position, whereas the lever can be actuated not only by the automatic releasing device but also by the operating member in such a manner that it can release the second spindle and simultaneously 25 the locking device.

One form of the free-turning coupling as applied to a high-tension oil-circuit breaker for three-phase current with direct maximum release by the secondary current of the 30 two current transformers is shown as example in the accompanying drawing.

Figure 1 shows a side view of the same partly broken away and partly in section. Fig. 2 shows a plan view, seen from above, 35 of a detail. Fig. 3 diagrammatically shows the corresponding electric connections.

1, in Figs. 1 and 2 of the high tension oil-circuit breaker is the actuating spindle on the cover 2 of which former the wire 40 clamp 3 (only one is shown) for leading in the main current is situated; the corresponding clamp for leading out the main current must be supposed to be situated behind.

45 4 is the front fixed contact and 5 the movable bridge contact piece which is fastened and insulated on a frame 6 movable up and down and can close and open the current between the front and back switch contacts.

50 The frame 6 is pivotally connected with a crank rod 7, which by means of the crank 8 mounted on the shaft 1, can raise and lower the frame 6 and thereby close or interrupt the circuit between 4 and 5. On 55 closing the circuit, a compression spring 10, situated on the rod 9 fastened to the cover

2 is compressed by means of the socket 11 connected with the frame 6. A socket 12 is rigidly mounted on the right end of the shaft 1 and carries a lever exposed to the 60 action of a spring 13 and turning on the shaft 14. One arm of the lever, which is pivoted crosswise to the spindle 1 carries a curved piece 15, which, on switching on the current, can pass beneath the slotted soft 65 iron core 16 of a solenoid 17 (Fig. 3).

In Fig. 1 the solenoid is inclosed in a slotted casing 18 and the leading in terminals 19, 20 correspond to the similarly designated terminals in Fig. 3. The iron core 70 is suspended from a spring 21, fastened to the slotted cover of the casing 18 (Fig. 3) which spring under normal conditions of current, as shown in Fig. 3, draws it out for the half part from the solenoid 17 and can 75 be regulated.

22 is an upwardly directed arm of the lever turning on the spindle 14. This arm carries three rollers 23 of which the lower engages in a recess 24 (Figs. 1 and 2) of a coupling disk 27 situated at the end of the shaft 25 of the hand wheel 26, this being effected under the action of a spring 13, and in this manner the shafts 1 and 25 are coupled with each other. The one side 28 of the recess 24 is so directed, that after the roller 23 has entered the recess 24, on turning the hand wheel 26 in the direction of the hands of a clock, it will carry around the said roller and with it the arm 22 and shaft 90 1; whereas the other side 29 of the recess is sloped so that on turning the hand wheel 26 in the opposite direction to the hands of a clock, the lowest one of the rollers 23 will be forced out of the recess and thus the 95 coupling between the shaft 1 and shaft 25 will be released. In this case the automatic switching off of the current between 4 and 5 proceeds under the action of the spring 10. In order to lock the actuating member in 100 the switched-on condition, a spring controlled pawl 30 is pivoted to the casing 18, behind which pawl the arm 22 with the roller 23 passes as soon as the current is switched on by turning the hand wheel 26 105 in the direction of the hands of a clock. A stop 31 situated on the disk 27 and a fixed arm 32 on the casing 18 will in this case prevent the hand wheel being turned too far.

If the switch is switched on and the electric current rises beyond the permissible degree then the core 16 will be drawn farther

into the solenoid 17 (Fig. 3) and will strike against the curved part 15 so that the lowest of the rollers 23 disengages from the recess 24; the coupling between the shafts 1 and 5 25 is released, simultaneously the uppermost roller comes out from the latch 30 and the switch is automatically switched off under the action of the compressing spring 10.

If the switch is in open position and the 10 parts 12 and 27 are coupled together, the spiral spring 33, fastened on the one hand to the shaft 1 and on the other hand to the disk 27, will not be under tension. If the switch is turned to closed position, the spring 15 33 is still not under tension, but if an overload occurs while the operator has hold of the handle 26, spring 33 will be wound up, and if handle 26 is released, it will be turned back to its initial position. In like manner 20 if an overload occurs after handle 26 has been released, it will also be turned back to its initial position. Also here appropriate stops 31 and 32 prevent the hand wheel 26 from being turned too far.

25 What I claim as my invention, and desire to secure by Letters Patent is—

In a non closable automatic electric circuit

breaker or the like the combination with the actuating spindle of an operating spindle, a coupling member fastened to one of the 30 spindles, a spring fastened on the one hand to the one of the spindles and on the other hand to the coupling member, a recess in the latter having the form of a trapezoid, a journaled lever pivoted crosswise to the 35 one of the spindles, a curved piece on the one arm of the lever, a spring, adapted to force the other arm of the lever into the recess of the coupling member in order to couple the actuating spindle with the operating spindle, an electric device which can actuate the curved piece in order to force the one arm out of the recess when predetermined currents pass the circuit breaker, a latching mechanism adapted to hold the 40 one arm of the lever fast when the current is switched on, all substantially as described.

In testimony whereof I have signed my name to this specification in the presence of two subscribing witnesses.

KARL HÖHN.
